UNITED STATES PATENT OFFICE

EDWARD KIRBY BOTTLE, OF ELMIRA, NEW YORK, ASSIGNOR TO AMERICAN SALES BOOK COMPANY, LIMITED, OF TORONTO, ONTARIO, CANADA, A CORPORATION OF ONTARIO, CANADA

INDICATOR

Application filed July 10, 1930. Serial No. 467,037.

This invention relates to an indicator and checking device having improved structural and functional characteristics, and capable of use in numerous different associations, but primarily intended for employment in record or inscribing machines and specifically autographic registers.

In connection with registers as heretofore constructed, it is understood that it has been customary to provide a record comprising for example a plurality of superposed layers of inscription receiving material which record is disposed in a register or similar apparatus, passed over an inscribing station forming part of the same and thereupon suitably disposed of. With a view to simultaneously preparing a plurality of copies by a single inscription upon the uppermost sheet or strip of the pile, it is moreover customary to interleave between these strips layers or webs of copying material as, for example, carbon paper. These layers when of proper quality serve accurately to provide duplicate records up to a certain number. Thereafter, however, due to the exhaustion of the copying material, the lower records are not in certain instances as clean-cut as might be desired. For this reason, it is customary periodically to shift the layers or webs of copying material so as to present a fresh surface, but in many instances, an operator, due to negligence or absent-mindedness, does not attend to this shifting; this resulting in faint or otherwise imperfect copies.

With this in mind, it is an object of the invention to provide an indicating structure which as aforesaid may be employed in various associations, but is primarily intended for use on autographic registers, and by means of which, for example, an operator is automatically advised after a certain number of inscribing operations that it is necessary to shift the copying material so that perfect records may be assured.

A further object of the invention is that of constructing a register apparatus which will prevent a further operative manipulation of its mechanism after a certain number of inscribing operations until after the oper-

ator has shifted for example the copying webs.

A still further object is that of providing a mechanism of this character involving a relatively simple construction embodying a few and rugged parts, these parts being capable of ready association with a register or similar apparatus as at present constructed, and without the necessity of modification of such apparatus. Moreover, by means of the present invention, a mechanism is furnished which will operate over long periods of time with freedom from difficulties and which will function properly even in the hands of an inexperienced operator.

With these and further objects in mind, reference is had to the attached sheets of drawings illustrating one practical embodiment of the invention, and in which:

Fig. 1 is a fragmentary side elevation of a register;

Fig. 2 is a plan view thereof;

Figs. 3 and 4 are partly sectional side views of the indicating and locking mechanism employed and showing the same in different positions; and

Fig. 5 is a plan view of one of the elements of such mechanism.

In these views, the reference numeral 10 indicates a base of the apparatus from which side walls 11 extend upwardly to support a deck 12 provided with an opening framing the face of the upper layer 13 of a record. This record is disposed within the casing of the register and is fed across the inscribing station provided by the opening in the plate by means of any suitable apparatus such as for example a friction drive indicated in dotted lines at 14 which is mounted upon a shaft 15 turned by a crank 16. Cooperating with this drive is a friction roller 17 mounted upon a support 18 normally retained in position by a catch 19. When so retained, proper cooperation between the record and the drive is assured, and when released, the plate 12 may be swung around its hinge 20 by releasing the catch 21.

Moreover, connected with the shaft 15 or any other suitable part of the apparatus is a ratchet and pawl construction (not shown)

which prevents an operator from accidentally turning the shaft 15 in a wrong direction, it being thus apparent that as the crank is rotated, the record is fed forwardly the distance of one pack of sheets. Thereafter, it is usually necessary to release the stop pin 22 in order that the crank may again be rotated, the pin thus serving to prevent an overfeeding of the latter.

10 One of the carbon layers or other copying strips has been indicated at 23, this strip extending between the plate and the side wall, and being initially wound upon a roller 24. This layer or any desirable number of 15 layers may be interleaved between the layers of the record extending transversely thereof and as afore brought out, it is necessary periodically to shift the copying material.

Now with a view to providing a mechanism 20 which will serve to indicate the necessity for such shifting and/or to prevent further manipulation of the register until such shifting has been achieved, it will be noted that in the embodiment of the invention illustrated, the 25 shaft has been extended and terminates in an enlarged screw threaded portion 25. Extending parallel to the axis of the shaft is a rod 26 upon which is slidably mounted a cam 27 having a threaded portion 28 curved to 30 correspond to the curvature of the enlarged portion 25 and to cooperate with the screw threads of the latter. The edge 29 of the cam beyond this threaded portion is developed in the form of a wedge shaped surface 35 terminating in an outwardly extending lip or ledge portion 30. Any desired means may be provided for assuring cooperation between the threads of the edge 28 and the enlarged portion 25. In the embodiment under consideration, a weight 31 has been employed for this purpose and is secured to the lower portion of the cam and to one side of the shaft 26. Additionally, the cam may carry a rod 32 having a signal in the nature of a 40 flag 33 at its outer end, it being apparent that if the parts move to the position shown in Fig. 4, this signal will be in a position such that the operator's attention will be directed to it.

45 Considering the functioning of the parts, it will be understood that with the apparatus disposed in the manner shown in Figs. 1, 2 and 3, the operator may, in the usual manner inscribe the record and periodically feed the same by means of the crank 16 or other driving element provided for this purpose. Upon each revolution of the shaft 15, the cam will move inwardly along the rod 26 to a distance corresponding to the distance between the convolutions of the thread upon the enlarged end portion 25. After a predetermined number of operative cycles of the feeding mechanism which may be 50 more or less as desired, the cam which has initially been set at the outer end of the por-

tion 25 will feed along the rod 26 until it rides within the recess 34 formed in this enlarged portion and interrupting the threads thereof. When this occurs, the weight or other shifting medium will serve 55 to swing the cam and the latter will drop to a point at which its edge projects into the recess 34 with the lip or ledge portion 30 in wedging contact with, for example, the end portion of this recess. Under these circumstances, the visual indicating means provided by the signal 33 will be within the immediate range of vision of the operator and additionally, the cam will prevent a further rotation of the shaft 15. In this connection it 60 will be understood that the cam edge 29 operates with the enlarged portion 25 in a plane above the axis of the latter and consequently wedges thereagainst. However, this is only an illustrative form of device for 65 accomplishing the desired function and it will be understood that other forms may be substituted.

It will be noticed that the record feeding mechanism will be checked after each record 70 feeding cycle by engagement of the crank 16 with the stop pin 22. This feeding cycle of the feeding mechanism may be defined as a sufficient operation thereof to move the records or record strips sufficiently to bring new 75 sets of forms or inscription areas into writing position after inscriptions have been made upon the next adjacent advance set of forms. In the embodiment shown this feeding cycle is completed by a single revolution of the feed shaft 15 but it will be understood that other forms of feed mechanism may be used wherein a feeding cycle may be completed by fractional revolution of the feed shaft or by 80 a plurality of revolutions thereof, the invention being independent in this respect of the precise form of feeding mechanism.

Furthermore, it will be seen that the indicating and feed checking means is operated to perform its indicating and checking functions only after a predetermined number of feeding cycles of the feeding mechanism; in other words, the checking and indicating functions are completed in response to a plurality of feeding cycles. After the feed has 85 been thus checked and the indicator displayed, the operator may reset the parts and to do this the top plate 12 may be swung upwardly after releasing the catch 21 thus rendering the interior mechanism accessible to 90 permit resetting the cam 27. In other words the cam may then be shifted to a point at which its screw threaded portion 28 rides at 95 contact with the first convolution of the threads upon the enlarged portion 25. However resetting of the cam 27 may be more conveniently accomplished merely by swinging it in a clockwise direction (Fig. 1, 3 and 4) 100

until the screw threaded portion 28 moves upwardly to disengage the threads of the enlarged portion or worm 25 whereupon the cam is freed and may be slid outwardly along the supporting bar 26 independently of movement of the feeding mechanism. The slot 34 may be formed to permit this disengaging clockwise rotation of the cam 27 from its locking position in which the detent 30 is wedged against the bottom of the slot. While the parts are open for releasing the ratchet or otherwise, the carbon may be gripped and pulled forward to present a fresh copying surface. Thereupon, by simply 15 swinging the support 18 downwardly and engaging the catch 19 after having swung the plate 12 to closed position, the machine is again ready for operation upon the stop pin 22 being released and this cycle of operation 20 is repeated indefinitely.

Thus, among others, the several objects of the invention as afore brought out are achieved. It will moreover be understood that numerous changes in construction and 25 rearrangements of the parts might be resorted to without in the slightest departing from the spirit of the invention as defined by the claims.

Having described my invention, what I 30 claim as new and desire to secure by Letters Patent, is:

1. An inscribing machine including a feeding mechanism to shift a record, an indicator, and indicator actuating means responsive 35 only to a predetermined plurality of actuating cycles of said feeding mechanism to indicate a predetermined condition with respect to said machine.

2. An inscribing machine including a feeding mechanism to shift a record, means operating in response to a plurality of feeding actuations of said feeding means to prevent a further operation thereof, and signalling means associated with said last named means 45 to register the condition of the latter.

3. An inscribing machine including a shaft, record feeding means connected to said shaft, and means also connected to said shaft and operating in response to a predetermined 50 plurality of feeding cycles of said feeding means to prevent further movement thereof.

4. An inscribing machine including a shaft, record feeding means connected to said shaft, an indicator connected to said shaft and providing a visual signal, and means responsive to a predetermined plurality of feeding cycles of the feeding means to display said visual signal.

5. An inscribing machine including a record feed operating shaft, means for rotating the same, and means associated with said shaft and having locking engagement therewith after a predetermined plurality of record feeding cycles of the latter to prevent 55 further movement thereof.

6. An inscribing machine including an operating shaft, means for rotating the same, normally inoperative signalling means associated with said shaft, and means connecting said signalling means to said shaft and functioning after a predetermined number of revolutions of the latter to shift said signalling means to operative condition. 70

7. An inscribing machine including an operating shaft, means for rotating the same, a screw threaded member operatively connected for rotation by said shaft, said member being formed with a peripheral recess, and a locking dog in engagement with said thread and shiftable automatically under 80 the rotation of said shaft to extend into said recess whereby to prevent further shaft movement.

8. An inscribing machine including an operating shaft, means for rotating the same, a screw threaded member secured to and moving with said shaft, said member being formed with a recess, means in engagement with such screw thread and shiftable to extend to a position to drop within said recess and signalling means actuated upon said last named means occupying a position within 85 said recess.

9. An inscribing machine including a record feeding shaft, means for rotating the same, a screw threaded member operatively connected to said shaft and formed with a recess adjacent its thread, a rod extending parallel to said shaft and adjacent said member, and means slidably disposed upon said rod and bearing against the threads of said member to ride within said recess upon said shaft being rotated a predetermined number of times, and said means preventing further rotation of said shaft upon its coming to 100 extend into said recess. 105

10. An inscribing machine including a record feeding shaft, means for rotating the same, a screw threaded member secured against movement with respect to said shaft and formed with a recess interrupting certain of the convolutions of its thread, and a cam member cooperating with said thread and shiftable to extend into such recess, said cam member having a portion of its edge threaded and curved to conform to the curvature of said first named member. 110 115

11. An inscribing machine including a record feeding shaft, means for rotating the same, a screw threaded member secured against movement with respect to said shaft and formed with a recess interrupting certain of the convolutions of its thread, a cam member cooperating with said thread and shiftable to extend into such recess, said cam member having a portion of its edge threaded and curved to conform to the curvature of said first named member, and an extended part associated with said cam and having 120 125 130

- locking engagement with one of the end walls of said recess.
12. In an inscribing machine, in combination, a record controlling mechanism, an indicator having operative connection for operation by said controlling mechanism, and means included in said operating connection for controlling the indicator for response only to a predetermined plurality of record controlling cycles of said record controlling mechanism.
13. In an inscribing machine, in combination, a record feeding mechanism, a locking device for checking operation of said feeding mechanism, and means operating only in response to a plurality of feed actuating cycles of said feeding mechanism to cause actuation of said locking device to check further operation of said feeding mechanism.
14. In a record machine, in combination, record feeding mechanism, means for checking said feeding mechanism after a feeding cycle thereof, and means for checking said feeding mechanism in response to a plurality of feeding cycles thereof.
15. In a record machine, in combination, record feeding mechanism, automatic checking means for checking said feeding mechanism after each feeding cycle thereof, and automatic checking means controlled by said feeding mechanism in response to a plurality of feeding cycles thereof.
16. In a record machine, in combination, record feeding means including a shaft, an indicator, and operating connections between said shaft and indicator for operating the latter in response to a predetermined plurality of feeding cycles of the shaft to indicate completion of said cycles.
17. In a record machine, in combination, a record feeding shaft, means for rotating said shaft, a screw threaded member operatively connected to said shaft, a locking device for said feeding shaft, and operating means for said locking device including an operating member in operative engagement with said screw thread and operative to set said locking device after a predetermined advance thereof by said thread.
18. In a record machine, in combination, a record feeding shaft, means for rotating said shaft, a screw threaded member operatively connected to said shaft, a locking device for said feeding shaft, operating means for said locking device including an operating member in operative engagement with said screw thread and operative to set said locking device after a predetermined advance thereof by said thread, and a support for said operating member mounting it for movement to disengage the threads to permit resetting of said operating member.
19. In an inscribing machine, in combination, means for feeding a record having copying material between the layers there-
- of, an indicator for said material, and means for actuating said indicator periodically in response to a plurality of feed actuations of said record feeding means.
20. In an inscribing machine, in combination, means for feeding a record having copying material between the layers thereof, an indicator for said material, means for actuating said indicator periodically in response to a plurality of feed actuations of said record feeding means, and means for checking operation of said feeding means only after a plurality of feeding cycles thereof.
